UNITED STATES PATENT OFFICE.

JAMES M. ADAMS, OF CHICAGO, ILLINOIS.

SALVAGING APPARATUS.

1,412,202.

Specification of Letters Patent. Patented Apr. 11, 1922.

Application filed October 28, 1921. Serial No. 511,011.

To all whom it may concern:

Be it known that I, JAMES M. ADAMS, a citizen of the United States, residing at Chicago, in the county of Cook and State of Illinois, have invented new and useful Improvements in Salvaging Apparatus, of which the following is a specification.

This invention is directed to means for salvaging vessels, and it has particular reference to apparatus for establishing connection with sunken vessels from above the surface of the water, for the purpose of bringing such submerged vessels clear of the bottom, and for towing such vessel, still 10 submerged, to a salvaging station, there to be raised and repaired.

To this end my invention resides in the combinations hereinafter clearly set forth and explained, and illustrated in the accompanying drawings, of which:

Fig. 1 is a general view indicating the method employed for taking hold of a foun- 20 dered vessel and towing it to a place of safety,

Fig. 2 illustrates auxiliary power means attachable to a sunken vessel for salvaging purposes,

Fig. 3 shows a modified form of salvaging apparatus,

Fig. 4 is a "close up" view of portions of the device of Fig. 3,

Fig. 5 illustrates auxiliary devices applica- 30 ble to the apparatus, as will hereinafter appear.

The relation of the structure of Fig. 6 will also appear upon reading the following detailed description.

In Fig. 1, the sunken vessel 1 is seen carried along by a plurality of salvaging ships, and this view illustrates one of the important features of the invention. Means have heretofore been suggested, as will presently be explained, for making connection to set a sunken ship on its keel and for raising it to the surface. It will require a great deal of power to raise a ship in such manner, and having brought the ship partly above the surface, it will be necessary to pump the water out of the hull, and likely to repair injuries sustained in foundering, in order to make the ship float. Divers would have to be employed for the purpose of inspecting the hull before it would be profitable to start pumping operations, and also to make such repairs of sub- 40 merged portions of the vessel. Wind and

wave would often make such operations very hazardous.

According to my invention the vessel will be raised sufficiently merely to clear ob- 55 structions on the sea or river bottom. The ship will then be towed to a suitable salvag- 60 ing station, which may be a floating and sub- 65 mergible drydock, or it may be an inclined runway, such as commonly used in ship 70 yards. In the first instance connection with the sunken ship is established from salvaging 75 vessels 2 and 3, whereupon these ships will proceed to set the sunken ship on its keel and to lift it clear of the bottom. Connection is then made from the towing ship 4, 80 whereupon all the salvaging ships are set in motion, the towing ship doing most of the dragging. The bow of the submerged 85 vessel should be held slightly higher than the stern, substantially in line with the tow- 90 line from the towing ship 4, whereby the submerged vessel is urged ahead in this plane, and the crews of the salvaging vessels should then gradually draw in on their lines, 95 causing a gradual elevation of the vessel to suit conditions. Most ships sink at a depth of five hundred feet or less, and the bottom is generally found to rise gently until it reaches the shore line. The incline of the 100 vessel and the gradual elevation should be relative to such bottom inclination.

It may be well to apply some motive power in close proximity to the submerged vessel, and on account of its great flexibility electricity has been found suitable for this purpose. Within the ship 4 is installed a plant for generating electric power, and this power is, through cables 5 and 6 transmitted to an electric motor 7, which in turn operates a propeller in close proximity to the vessel. This propeller has the function of applying motive power at the place where it is needed, and it has the further advantage of agitating the water around the hull, thereby operating to sweep away from the hull all sand which may have accumulated.

The mechanism for towing the submerged vessel and the means for attaching an electric motor, are readily understood by refer- 105 ring both to Fig. 1 and Fig. 2. Suitably anchored in the sunken ship 1 is a spear shaped member 10 having a conical head 10^a, and made with a central longitudinal passage 10^b. Stored within the ship is a buoy line 13, which is caused to extend 110

through said passage, whereupon the end of the line is made fast to a floating member, such as the buoy 14 shown in Fig. 4. When the ship sinks below the surface this 5 buoy will be urged to float, and it will remain on the surface giving permanent indication of the position of the sunken vessel. A float 15 may conveniently be mounted on the spear 10 for the purpose of urging 10 said spear into a vertical position. When the ship 4 appears near the place it will discover the buoy, which then is picked up and detached from the buoy line, whereupon the latter is pulled taut. For the purpose 15 of hauling this line taut, and in order to pull the spear 10 into a substantially vertical position, the buoy line is made with an enlargement 13^a, which is free to enter the passage 10^b, but which comes to a stop 20 against a shoulder portion 10^c. It is understood, of course, that the vessel 4, by pulling on the buoy line 13, has previously been enabled to maneuver itself into a position substantially perpendicularly above the 25 sunken vessel. The crew of the vessel 4 will then thread the end of the buoy line through a tubular rod 17, whereupon said rod is caused to slide down along the buoy line. The rod 17 terminates in a head 18 30 carrying a plurality of pawls 19, 20, which latter, through the medium of suitable springs 21, 22 are urged into engagement with the spear-head 10^a, when the rod reaches said spear. The opposite end of 35 the rod 17 terminates in a shoulder 23, which is shaped to receive a hauling cable 24. When connection has been made, as just described, it remains for the crew to pull in on the hauling cable 24.

40 Devices 25, 26, similar to the one just described, are found along the sides of the sunken vessel and on the salvaging vessels 2 and 3, and they are brought into engagement with each other in identically the 45 same manner, if desired. On the salvaging vessels may be installed power driven winches 28, 29, which in the first place are put into operation to place the sunken vessel on its keel and to raise it free of the 50 bottom, whereupon the vessel 4 commences the towing operation. In Fig. 1 the vessels 2 and 3 are, for the sake of clearness shown placed far apart, but I wish it understood that in practice they will seek a position 55 close together. The said vessels are shown proceeding under their own steam, but they may well be towed by the front vessel 4 also. Furthermore it may be found desirable to interconnect the two vessels, as indicated in Fig. 3, where one or more trusses 30 are shown suitably secured on the ships 31, 32, for the purpose of stabilizing the ships. It is not necessary that the vessels 35 2, 3 and 31, 32 be complete steamships, as 40 indicated, and in most cases it may be suffi-

cient and preferable to employ large barges or scows, and to interconnect such scows by trusses substantially as above described.

On the tubular rod 17 is secured a motor casing 35, within which the usual field magnets are secured and an armature 36 is also mounted to rotate in the casing, as usual in practice. This armature is rigid on a tubular shaft 37, which extends through the casing and serves to support a propeller 38. Suitable means, such as an antifriction washer 39, is provided to take the end thrust of the propeller against the head 18. From the vessel extend cables 40, 41, through which a circuit is closed, causing the motor 80 to start and to rotate the propeller. The spear head 10^a is fitted with flanges 10^d adapted to prevent rotation of the pawls 19, 20 on said head and consequent twisting of the cables 24.

85 Among the objections to sending the motor down to connect with the sunken vessel is the weight of the motor, furthermore there is difficulty in making the motor watertight. The problem of insulation is 90 also a difficult problem. For these reasons it may be better not to employ such motor, but in its stead to use flexible shaft connections to drive the propeller, and such a construction is illustrated in Figs. 3 and 4.

95 The spear mechanism may remain as hereinbefore described, but the tubular rod 51 is made with a head 52 having lateral arms 52^a, 52^b, and these arms are perforated to form bearings for a pair of propellers 53, 100 54. Within the vessel 55 are installed suitable power generating machinery, such as steam engines or electric generating sets (not shown), from which extend flexible shafts 56, 57 to the said arms and connected 105 to rotate said propellers. By means of suitable couplings 58 these shafts may conveniently be made in sections, so as to be more readily adapted to distance variations 110 between the sunken vessel 60 and the towing ship 55.

115 Conceivably it may at times be necessary to bring into service additional salvaging vessels, in order to carry particularly heavy hulls, and if all the vessels are interconnected, as shown in Fig. 1, it may not be advisable to stop and disconnect any of the connections. In that case special grapple tongs are provided, and such tongs 70 may be lowered along one of the cables 24, whereupon the cable 71 of the tongs may be picked up by such additional vessel (not shown). By referring to Fig. 5 it is readily seen that a pull on the said grapple cable 71 will have the effect of causing the tongs 70 to grip the 120 cable 24. The application of a number of such devices may, in an emergency, prove 125 very helpful, if not necessary.

I claim:

1. In a salvaging apparatus, means for 130

making connection with a sunken vessel from above water for the purpose of raising said vessel clear of the bottom, said means including a pair of propellers, flexible shafts 5 extending from above water to said propellers for the purpose of rotating the same, and means for towing the submerged vessel to a place of safety.

2. In a salvaging apparatus, means for 10 making connection between ships above water and a sunken vessel for the purpose of raising said vessel above the bottom, means for towing the submerged vessel to a place of safety, said means including one or more 15 propellers, and means extending from above the surface for driving said propellers.

3. The combination with a sunken vessel, 20 of a towing ship, a buoy line extending from said vessel to the surface, a towing cable slidable along said line to connect with the vessel, a yoke on said cable, propellers mounted in said yoke, and means extending from the towing ship for rotating said propellers.

4. A towing ship, a submerged vessel, a 25 connecting member on said vessel, a line terminating in a buoy and extending from said member to the surface, a cable connection terminating in a head and slidable down said line for connecting with said member,

one or more propellers rotatable in said head, 30 and means extending from the ship for driving said propellers.

5. In a salvaging apparatus, means for connecting with and carrying a sunken vessel, a towing ship, means for connecting said ship with the said vessel, said means including propellers attachable to said vessel.

6. In a salvaging apparatus, means connectable above water with a sunken vessel for raising said vessel clear of the bottom, 40 a towing ship, a floating member suspended from the sunken vessel, means on the towing ship slidable down the suspension line of said floating member for making towing connection with the vessel, said means including auxiliary propellers.

7. The combination with a towing ship and a sunken vessel, of a towing line, means for attaching said line to the sunken vessel from above water, propellers mounted on 50 said towing line, and flexible shafts extending from the towing ship to drive said propellers, said shafts made in sections by means of suitable couplings.

In testimony whereof I have hereunto 55 affixed my signature.

JAMES M. ADAMS.
